ELEVATOR

James Dunlop, Ridgewood, and Lennie E. Rissler, Hohokus, N. J., assignors, by mesne assignments, to Westinghouse Electric Corporation, East Pittsburgh, Pa., a corporation of Pennsylvania

Application December 29, 1943, Serial No. 516,046

10 Claims. (Cl. 187—95)

1

Our invention relates to elevators and more particularly to the use of shock absorbing devices for preventing injury to elevators.

In a typical airplane carrier ship provided with a deck edge elevator for transferring airplanes to and from its flight deck, the flight deck overhangs the edge of the ship about 16 feet and out of this overhanging part of the deck is notched a space for the elevator platform which is about 60 feet long and 34 feet wide and which weighs approximately 60 tons. The outboard portion of the platform extends approximately 18 feet beyond the overhanging edge of the flight deck. The guide rails for the platform are mounted on the outside face of the ship hull and the platform is suspended and operated in the guide rails by a plurality of hoisting cables which pass over sheaves mounted on the underside of the overhanging part of the deck and which are attached to the fore and aft ends of the platform. The platform is suspended entirely by its hoisting cables and is not counterweighted.

In elevators of this character, many difficult operating conditions are encountered. For instance, when the ship heels over 20°, the elevator platform may be submerged in the water. If the speed of the ship is high, the water drag will tend to tear the platform off the side of the ship. The maximum water drag in the fore and aft directions under such circumstances may be more than the guide shoes on the platform can stand, thus resulting in damage to the guide shoes or the platform or the elevator structure.

One object of our invention is to provide a shock absorbing means for an elevator platform which will enable its roller guides to carry the guiding loads until they reach a predetermined value and if the guiding loads increase beyond that value to absorb them with an increasing resistance and finally transfer them to the structure in which the platform is mounted when they increase beyond a second predetermined value.

Another object is to provide a guide shoe for elevator platforms which will safely guide the movements of the platform while it is in normal operation and which will absorb additional forces to which the platform may be subjected without being damaged itself and without permitting any damage to the platform or the structure in which it operates.

A further object is to provide a guiding means for a ship elevator platform which will absorb excessive shocks to the platform and permit it to settle slowly and firmly against the ship structure without having a battering-ram effect on the ship when the shocks exceed a predetermined value.

2

It is also an object to provide an elevator platform safety guide shoe which shall be simple in construction, positive in operation, and which may be easily manufactured, installed, and maintained ready for shock absorbing operation.

For a better understanding of the invention, reference may be had to the accompanying drawings, in which:

Figure 1 is a view in side elevation, looking in the outboard direction from the interior of a ship, of a deck-edge elevator, embodying our invention, parts of the guide rails being shown in section.

Fig. 2 is an enlarged view in top elevation of one of the guide shoes illustrated in Fig. 1.

Fig. 3 is an enlarged view in side elevation and partially in cross section of the guide shoe shown in Fig. 2.

Fig. 4 is an enlarged view in cross section of the bending bar in Fig. 3.

Fig. 5 is a view taken on the line V—V of Fig. 3, and

Fig. 6 is a view taken on the line VI—VI of Fig. 5.

Although the invention is illustrated in connection with a deck-edge elevator for an airplane carrier ship, it may be used in connection with any elevator or other large body in which it is necessary to protect the parts from more than predetermined forces.

Referring more specifically to the drawings, we have illustrated a deck edge elevator having a platform 10 disposed between a pair of guide rails 11 and 12 mounted on the outside of a ship hull 13 (only a small portion of which is shown) in position to be supported by and to be raised and lowered between a main deck (not shown) and a flight deck 15 by a plurality of hoisting cables 16 and 17 attached to its fore and aft ends by hitches 18 and 19. The hoisting cables may be operated by any suitable means, such as a hydraulic engine like that illustrated and described in the copending application Serial No. 515,992, filed Dec. 28, 1943, and assigned to the Westinghouse Electric Elevator Company.

The platform 10 may be constructed of seamless steel tubing, structural steel sections and steel plate welded together in bridge-like form to form a relatively light but strong structure 20.

The guide rails 11 and 12 are provided with channeled faces 21 and 22 facing each other and are mounted on backing plates 23, 23a, 24 and 24a. The backing plates are secured to the ship hull by a plurality of horizontal brackets 25 and 25a which are welded thereto to provide a strong support for the guide rails.

The platform is guided in the guide rails by

four roller type guide shoes 27, 28, 29 and 30. The guide shoes 27 and 29 are mounted one above the other on the aft end of the platform for engaging the channel 21 in the guide rail 11. The guide shoes 28 and 30 are mounted one above the other on the fore end of the platform in position to engage the channel 22 in the guide rail 12.

Referring to Figs. 3 to 6, the guide shoe 27 comprises a housing 32 and a side roller 33 and an end roller 34 mounted therein. The guide housing is securely fastened to the platform framework 20 by a plurality of bolts 35. The side roller 33 is mounted on a shaft 36 rotatably mounted in the upper cylindrical portion 37 of the housing 32, so that it will run between the side faces of the channel 21 to control the platform athwart ship. Renewable hardened steel strips 38 and 39 are mounted on the side-walls of the channel to reduce the amount of wear.

The guide roller 34 is disposed to engage the inner face of the channel 21 to prevent end movement of the platform and is rotatably mounted on a pin 41 disposed in the forked end of a round shaft 42, slidably disposed in the lower cylindrical portion 43 of the housing 32.

The end roller 34 is biased into engagement with the inner face of the channel 21 by a coiled compression spring 44 disposed between the central face of a cavity 45 in the rear-end of the roller shaft and the inner face of a cap 46, which is mounted on the rear end of the cylinder 43 by a plurality of bolts 47. A similar spring is mounted back of each of the other end rollers to bias them into contact with the guard rails and to centralize the platform between the guide rails. The springs are selected with a steep characteristic to balance the weight of the platform, so that they will absorb the normal end thrusts of the platform.

The shaft 42 is prevented from rotating in the body 32 by a pair of fins 48 on the inner side of the cap 46 which extend into slots 49 on the end of the shaft, so that the end roller 34 will always track in a vertical direction in the channel 21. A pair of bolts 51 and 52 pass loosely through the cap 46 and screw into the rear-end of the shaft 42. The bolts 51 and 52 are used only during assembly to hold the spring compressed until the platform is properly aligned with the guide rails. After the platform is correctly positioned in the guide rails, the bolts 51 and 52 are removed and water tight plugs are inserted in the holes. The spring is then free to press the roller against the rail.

In order to limit the rearward movement of the end roller when the end thrusts of the platform reach a value sufficient to compress the spring 44 a predetermined distance, we have provided a projection or shank 54 on the rear end of the shaft 42 and tipped it with a hardened striking bar 56 disposed to engage a bar 57 in the rear end of the cylinder when the end roller is forced inwardly a predetermined distance. The parts are so constructed and mounted as to provide a normal space or clearance of say one-eighth inch between the striking bar and the bending bar for permitting that much spring biased play of the end roller during normal conditions.

The normal end thrusts of the platform will be taken care of by the compression spring and the engagement of the striking bar with the stop bar. However, if the ship heels or rolls while moving at high speed to such extent that the

platform strikes the water, the water drag thereon may exert a maximum end thrust as high as 800,000 pounds. A practical guide shoe can not be made which will stand more than approximately 50,000 pounds. Hence it will be apparent that it is not practical to build the guides and rollers strong enough to take the end thrusts and particularly the twisting moment that develops when the platform dips into a wave when the ship is moving with speed. If the guide parts were made so that they would take all end thrusts, they would be so heavy as to require a heavier platform which, in turn would require a heavier engine, etc., the whole construction becoming impractical. Therefore, we have so constructed and mounted the striking bar and the stop bar that the stop bar will bend when the end thrust exceeds a predetermined value and thus limit the stress to a predetermined amount, that can be exerted up to the point where the excessive thrust is taken by slipper blocks designed to withstand the force.

The striking bar 56 is mounted on the rear-end of the shank 54 by a press fit and a pin 58. The stop or bending bar 57 is disposed with its ends resting on a pair of shoulders 59 at the sides of a depression in the inner face of the cap 46 and is secured in that position by a pair of brass screws 60 which pass through its ends into the cap. When the force exerted by the platform on the guide shoe exceeds a predetermined value, the striking bar will be forced against the center of the bending bar and bend it into the space 61, thus relieving the strain on the end roller.

The bending bar 57 is so selected as to size and strength that it will bend and permit the end roller 34 to compress the spring 45 more than one-eighth inch only when a predetermined dangerous pressure tends to move the platform end-ways. It is also desirable to provide for increasing the resistance of the bending bar as the bending continues. Therefore, the bearing edges of the shoulders 49 for the bending bar are rounded so that the span of the bending bar decreases at it bends. After a bending action of the bending bar, its condition may be readily detected by the looseness of the end roller in operation and the bent bar may be easily replaced by removing the cap 46 and substituting a new bar for the old one. In a given installation the rounded edge may be made with a one-sixteenth inch radius and the bending bar will reach its yield point at approximately 29,000 pounds and attain a three-fourths inch deflection at approximately 57,000 pounds. While these measurements and weights given so far have been taken from an existing installation, it is to be understood that other installations of this invention may vary considerably in their measurements, etc., from those here given.

The guide shoes 28, 29 and 30 are constructed in the same manner as the guide shoe 27.

It is desirable to have the end thrust of the platform transferred from the bending bar to the ship structure as the force of the thrust approaches the limit for which the bending bar is designed. In order to accomplish this, we have mounted a plurality of slipper blocks 64, 65, 66 and 67 (Fig. 1) on the platform 10 in position to engage the backing plates 24 and 24a mounted on the brackets 25 and 25a at the side of the ship as the bending bars reach their limits of deflection. The slipper blocks 64 (Fig. 2) are disposed adjacent to the guide shoe 27 and is mounted on the platform 10 by a beam 69 in position

to engage the backing plate 24 on the brackets 25 when the end thrust of the platform approaches the deflecting limit of the bending bar. The slipper blocks 65, 66 and 67 are similar to the slipper block 64 and are mounted adjacent to the guide shoes 28, 29 and 30, respectively by beams 69a, 69b and 69c on the platform frame 20. The location of the slipper blocks at the points indicated in the drawings give them a low leverage on the ship structure so that they can withstand the forces involved.

If the platform is moving up or down when the slipper blocks engage the plates 25, they will slide along the plates while resting the end thrust of the platform against the ship. The distance between the slipper blocks and the plates should be approximately equal to the deflection of the bending bars so that the end thrust of the platform will be transferred to the ship just as the bending bars reach their greatest resistance to the end thrust.

From the foregoing description, it will be apparent that with the ship in normal operation in normal seas, the normal end thrusts of the platform on the end rollers in its guide shoes will be absorbed by the compression springs 44 and the springs will tend to centralize the platform between the guide rails. It will also be apparent that if an end thrust of the platform reaches a predetermined value at either end of the platform, it will compress the springs at that end to a point where the striking bars thereat will engage the bending bars back of them and limit the rearward movement of the end rollers. In this case the force of the end thrust, say, 11,400 pounds, for example, is absorbed by the springs.

If the ship, while moving forward at high speed, rolls over until the platform dips into the water, the resulting water drag may apply to the platform a force greater than the end rollers in the aft guide shoes can stand without being damaged. Assuming that the force of the water drag increases beyond the predetermined force necessary to move the end rollers to their rearward limit and reaches a second predetermined value, say, 29,000 pounds (the yield point of the bending bar under consideration), then the striking bars will deflect the bending bars and that deflecting action of the bending bars will absorb much of the force of the water drag. As the force of the water drag increases, the bending bars will provide an increasing resistance to the end thrust of the platforms because the span of the bars is decreasing by reason of the rounded edges of the shoulders on which they are mounted and thus an increasing absorption of the end thrust by the bending bars occurs.

Assuming now that the end thrust created by the water drag increases still further, say, beyond 50,000 pounds, then as the bending bars near their deflecting limit, the slipper blocks at the aft end of the platform will move into contact with the backing plate 24a and thus transfer the end thrust of the platform to the ship structure.

From this it will be apparent that we have provided for absorbing various degrees of end thrust forces of the platform until they exceed a predetermined value and that when they exceed that predetermined value, they are transferred to the ship structure without shock or a battering ram effect by the platform on the ship.

Although we have illustrated and described only one specific embodiment of our invention, changes and modifications therein may be made without departing from its spirit and scope. Furthermore,

it should be understood that the dimensions, weights, etc., noted in the description are given merely as examples and are not intended to limit the application of the invention in any manner.

We claim as our invention:

1. A guide shoe for a platform comprising a housing, an end guide member slidably disposed in the housing, means for biasing the guide member outwardly, and a bar seated across a pair of shoulders in the rear of the housing for limiting the inward movement of the guide member, said bar having a predetermined failure point at which it will be deflected upon the application of a predetermined inward pressure by the guide member.

2. A guide shoe for a platform comprising a housing, an end guide member slidably disposed in the housing, means for biasing the guide member outwardly, and a bar seated across a pair of shoulders in the rear of the housing for limiting the inward movement of the guide member, said bar having a predetermined failure point at which it will be deflected upon the application of a predetermined inward pressure by the guide member; and said shoulders having rounded bearing edges for the bar to decrease the span of the bar as it is deflected and thereby provide an increasing resistance to further deflection of the bar.

3. A guide shoe for a platform comprising a housing, with a cylindrical opening, an end guide member slidably disposed in the cylindrical opening, means for preventing rotation of the guide member in the opening, means for biasing the guide member outwardly, and a bar disposed in the inner end of the cylindrical opening for limiting the inward movement of the guide member, said bar having a predetermined failure point at which it will be deflected when the rearward movement of the guide member exceeds a predetermined value.

4. In an elevator, a pair of guide rails, a platform disposed between the guide rails, a guide mounted on each end of the platform in position to engage the guide rail thereat for guiding the platform between the guide rails, a means for biasing each guide toward the guide rail adjacent thereto and for absorbing the end thrust of the platform up to a predetermined pressure, and a substantially non-resilient bar for limiting the rearward movement of each guide to a predetermined distance when said end thrust pressure exceeds said predetermined pressure, and for permitting a further rearward movement of that guide only when the end thrust pressure exceeds a second predetermined pressure sufficient to permanently deform the bar for providing a predetermined resistance to said further rearward movement of each guide.

5. In a deck edge elevator for a ship, a pair of guide rails, a platform disposed between the guide rails, a guide mounted on each end of the platform in position to engage the associated guide rail for guiding the platform, a means associated with the guide for absorbing the end thrust of the platform up to a predetermined pressure, a bending bar associated with the guide for absorbing the end thrust of the platform when it exceeds said predetermined pressure up to a second predetermined pressure, and a slip plate mounted on the ship at each end of the platform for applying the unabsorbed end thrust of the platform to the ship structure when the end thrust exceeds said second predetermined pressure.

6. In a deck edge elevator for a ship, a pair of guide rails, a platform disposed between the guide rails, means for raising and lowering the plat-

form, an upper guide shoe housing and a lower guide housing mounted on each end of the platform, a guide member slidably mounted in each guide housing, with its outer end disposed in position to engage the guide rail adjacent thereto, for guiding the platform, a biasing means mounted in each guide housing for biasing the guide member thereof toward the adjacent guide rail, and for absorbing the end thrust of the platform up to a predetermined pressure, a bending bar disposed on a pair of shoulders in each housing for limiting the rearward movement of the guide member when the end thrust exceeds said predetermined pressure, said bending bar being constructed with a predetermined yield point so that it will be deflected when the end thrust pressure exceeds a second predetermined value and said shoulders having rounded bearing edges for the bar to decrease its span as it bends and thereby provide an increasing resistance to further bending of the bar, a plate mounted on the ship at each end of the platform, and a slipper block mounted on the platform in position to engage the plate adjacent thereto when the bending bar is deflected a predetermined distance for resting the platform against the ship structure when the end thrust pressure exceeds a third predetermined pressure.

7. In a deck edge elevator for a ship, a pair of guide rails, a platform disposed between the guide rails, means for raising and lowering the platform, an upper guide shoe housing and a lower guide housing mounted on each end of the platform, a shaft slidably disposed in each guide shoe housing, an end roller mounted on the outer end of each shaft in position to engage the guide rail adjacent thereto for guiding the platform, a spring mounted in each guide shoe housing for biasing the shaft and roller thereof toward the adjacent guide rail, and for absorbing the end thrust of the platform up to a predetermined pressure, a bending bar disposed on a pair of shoulders in the housing for limiting the rearward movement of the shaft and roller until the end thrust pressure exceeds a second predetermined value, said bending bar being constructed with a predetermined yield point so that it may be deflected when the end thrust pressure exceeds said second predetermined value, a plate mounted on the ship at each end of the platform, and a slipper block mounted on each end of the platform in position to engage the plate adjacent thereto when the bending bar is deflected a predetermined distance and thereby rest the platform against the ship structure when the end thrust pressure exceeds a third predetermined value.

8. In a deck edge elevator for a ship, a pair of guide rails, a platform disposed between the guide rails, means for raising and lowering the platform, an upper guide housing and a lower guide housing mounted on each end of the platform, a shaft slidably disposed in each guide housing, an end roller mounted on the outer end of each shaft in position to engage the guide rail adjacent thereto, for guiding the platform, a spring mounted in each guide housing for biasing the shaft and roller thereof toward the adjacent guide rail and for absorbing the end thrust of the platform up to a predetermined pressure, a striking bar mounted on the rear end of each shaft, a bending bar disposed on a pair of shoulders in each housing for engagement by the striking bar therein to

limit the rearward movement of the shaft and roller when the end thrust pressure exceeds a predetermined value, said bending bar being constructed with a predetermined yield point so that it may be deflected when the end thrust pressure exceeds a predetermined value, and a slipper block mounted on each end of the platform in position to engage a portion of the ship structure when the bending bar is deflected a predetermined distance for resting the platform against the ship structure when the end thrust pressure exceeds a predetermined amount.

9. In a deck edge elevator for a ship, a pair of guide rails, a platform disposed between the guide rails, an upper guide housing and a lower guide housing mounted on each end of the platform, a shaft slidably disposed in each guide housing, an end roller mounted on the outer end of each shaft in position to engage the guide rail adjacent thereto for guiding the platform, a spring mounted in each guide housing for biasing the shaft and roller thereon toward the adjacent guide rail and absorbing the end thrust of the platform up to a predetermined pressure, a striking bar mounted on the rear end of each shaft, a bending bar disposed on a pair of shoulders in each housing for engagement by the striking bar therein to limit the rearward movement of the shaft and roller when the end thrust pressure exceeds a predetermined value, said bending bar being constructed with a predetermined yield point so that it may bend when the end thrust pressure exceeds a second predetermined value and said shoulders having rounded bearing edges for the bar to decrease the span of the bar as it bends and thereby provide an increased resistance to further bending of the bar, and a slipper block mounted on each end of the platform in position to engage a portion of the ship structure when the bending bar is deflected a predetermined distance for resting the platform against the ship structure when the end thrust pressure exceeds a predetermined amount.

10. In a deck edge elevator for a ship, a pair of guide rails, a platform disposed between the guide rails, a guide housing mounted on the platform, a guide member slidably mounted in the guide housing, with its outer end disposed in position to engage the guide rail adjacent thereto, for guiding the platform, a biasing means mounted in the guide housing for biasing the guide member thereof toward the adjacent guide rail and for absorbing the end thrust of the platform up to a predetermined pressure, a bending bar disposed on a pair of shoulders in the housing for limiting the rearward movement of the guide member when the end thrust pressure exceeds a predetermined value, said bending bar being constructed with a predetermined yield point so that it will be deflected when the end thrust pressure exceeds a second predetermined value and said shoulders having rounded bearing edges for the bar to decrease its span as it bends and thereby provide an increasing resistance to further bending of the bar, a plate mounted on the ship, and a slipper block mounted on the platform in position to engage the plate adjacent thereto when the bending bar is deflected a predetermined distance for resting the platform against the ship structure when the end thrust pressure exceeds a predetermined amount.
